(57) **CLAIM**

The ornamental design for a vehicle fender, as shown and described.

DESCRIPTION

FIG. 1 is a front view of a first embodiment of the vehicle fender of the present invention;
FIG. 2 is a front and left side perspective view thereof;
FIG. 3 is a front and right side perspective view thereof;
FIG. 4 is a right side view thereof;
FIG. 5 is a left side view thereof;
FIG. 6 is a rear view thereof;
FIG. 7 is a rear and left side perspective view thereof;
FIG. 8 is a rear and right side perspective view thereof;
FIG. 9 is a top view thereof;
FIG. 10 is a bottom view thereof;
FIG. 11 is a front view of a second embodiment of the vehicle fender of the present invention, which is a mirror image of the first embodiment;
FIG. 12 is a front and right side perspective view thereof;
FIG. 13 is a front and left side perspective view thereof;
FIG. 14 is a right side view thereof;
FIG. 15 is a left side view thereof;
FIG. 16 is a rear view thereof;
FIG. 17 is a rear and left side perspective view thereof;
FIG. 18 is a rear and right side perspective view thereof;
FIG. 19 is a top view thereof; and,
FIG. 20 is a bottom view thereof.
